UNITED STATES PATENT OFFICE.

LEONIDAS H. OLDFIELD, OF NEWTON, KANSAS.

STOVE-PIPE ANCHOR AND FLUE-CLEANER.

SPECIFICATION forming part of Letters Patent No. 404,553, dated June 4, 1889.

Application filed November 24, 1888. Serial No. 291,796. (No model.)

To all whom it may concern:

Be it known that I, LEONIDAS H. OLDFIELD, of Newton, in the county of Harvey and State of Kansas, have invented a new and Improved 5 Stove-Pipe Anchor and Flue-Cleaner, of which the following is a full, clear, and exact description.

The object of this invention is to provide for the locking of stove-pipes to the chimneys 10 to which they lead, and at the same time to provide for the cleaning of such pipes; and to the end named the invention consists, essentially, of a rod provided with a spur extending from one side and a plate extending from the other 15 side, and a catch or handle arranged in connection with the rod, all as will be hereinafter more fully explained, and specifically pointed out in the claims.

Reference is to be had to the accompanying 20 drawings, forming a part of this specification, in which similar figures and letters of reference indicate corresponding parts in all the views.

Figure 1 is a longitudinal sectional view 25 of a stove-pipe, representing the same as it appears when provided with my improved anchor and cleaner, the position of the device when used as a cleaner being indicated by dotted lines. Fig. 2 is an end view of the handle-socket, the weight arranged in connection therewith being partially broken away. Fig. 3 is a sectional view on line $x-x$ of Fig. 1. Fig. 4 is a side view of the anchor and cleaner, representing the same as it appears when provided with additional cleaners. Fig. 5 is a cross-sectional view of a pipe representing an auxiliary cleaner as arranged therein. Fig. 6 is a central sectional view of a stove-pipe tied in accordance with the terms of my invention. 30

40 In the drawings, 10 represents a horizontal length of pipe, 11 an elbow, and 12 a pipe-section leading to the stove-flange, the section 10 entering a chimney C, as indicated in Fig. 1. In order that the pipes 10, 11, and 12 may 45 be held against accidental displacement, I provide a rod or bar 13, formed with a spur 14 and an inclined branch or arm 15, and to the ends of the rod 13 and the arm 15 I connect a plate 16, preferably of the form shown 50 best in Fig. 3, the plate extending in a direction opposite to that in which the spur 14 extends. The arm 15 is connected with the plate

16 to be flush with the edge of the plate, so that the arm will guide the plate over joints and other irregularities in the pipe. The opposite end of the rod 13 is formed to enter the socket 17 of a weighted handle 18, the said socket being formed with a flattened portion a and being provided with a set-screw 19.

In applying my anchor it is passed through 60 an aperture b, formed in the elbow 11, and through the pipe 10, the spur 14 being turned down so as to bear against the outer flue-wall, while the plate 16 abuts against the inner flue-wall. About the extending end c of the rod 65 13 I place a plate 20, which serves to partially cover the aperture b, and I also place an inclined faced washer 21, whereby a square bearing is secured for the socket 17. The parts having been so applied, the thumb-screw 70 19 is turned down hard upon the end of the rod 13, thus locking all parts against displacement.

If it is desired to clean the stove-pipe, the handle 18 is turned up and the spur 14 freed 75 from engagement with the outer flue-wall and the end of the pipe 10, the rod 13 being turned until it is in the position indicated by dotted lines in Fig. 1, and being so turned it will be seen that all soot within the pipe 10 may be 80 readily removed by reciprocating the rod.

In certain cases the apartment within which the pipe 10 is placed might not be long enough for the entire withdrawal of the rod 13, and in such cases I would provide the rod with 85 auxiliary plates 23, said plates being hinged to clamps 24, that are secured to the rod 13. By this arrangement it will be seen that a shorter reciprocation will bring about the desired result, inasmuch as it is only necessary 90 to free the pipe to move the rod a little more than the space between the plates 23 and 16.

When the rod 13 is used as an anchor, the plates 23 assume the position indicated by 95 dotted lines in Fig. 5.

If a number of pipe-sections are to be joined together, simple tie-rods 25—such as those shown in Fig. 6—would be employed, said rods passing out through plates similar to the plate 20 and through inclined faced washers 21, to 100 engage socket tubes or collars 30, provided with thumb-screws 31.

In anchoring the stove-pipe section 12 to the flange of the stove I prefer to employ

such a device as that shown in Fig. 6, wherein in the rod 25 is represented as being provided with a number of plates 26, that are formed with shoulders *n*, which fit beneath and above the stove-top, the plates being held to place by a nut *m*.

Having thus described my invention, I claim as new and desire to secure by Letters Patent—

1. The combination, with a rod provided with a spur extending from one side, of a plate extending from the other side of the rod, and a handle connected with the rod, substantially as described.

2. The combination, with a rod provided with a spur which extends from one side, of a plate extending from the other side, a socket-

tube connected with the rod, and a weighted handle connected to the socket-tube, substantially as described.

3. The combination, with a rod 13, provided with a spur 14 and a plate 16, of a socketed weighted handle 18 and an inclined faced washer, substantially as described.

4. The combination, with a rod provided with a spur 14 and a plate 16, of auxiliary plates 23, and connections between the rods and plates, substantially as described.

LEONIDAS H. OLDFIELD.
